RAZOR CASE

Donald A. Leathers, South Easton, Mass., assignor to
The Gillette Company, Boston, Mass.

Filed Apr. 24, 1972, Ser. No. 247,259

Term of patent 14 years

Int. Cl. D9—03

U.S. Cl. D9—186

Fig. 1

Fig. 2

Fig. 3

Fig. 4

Fig. 5

Fig. 6

FIG. 1 is a perspective view of a razor case showing my new design;

FIG. 2 is a top plan view thereof;

FIG. 3 is a bottom plan view thereof;

FIG. 4 is a side elevational view, the opposite side being substantially a mirror image thereof;

FIG. 5 is a first end elevational view thereof; and

FIG. 6 is a second end elevational view thereof.

I claim:

The ornamental design for a razor case, substantially as shown and described.
